Primary Examiner — Patricia A Palasik(74) *Attorney, Agent, or Firm* — Andrew F. Young, Esq.; Lackenbach Siegel, LLP(57) **CLAIM**

The ornamental design for a sealing boot, as shown and described.

DESCRIPTION

FIG. 1 is a front top perspective view of a sealing boot.

FIG. 2 is a front elevation view of FIG. 1.

FIG. 3 is a rear elevation view of FIG. 1.

FIG. 4 is a left side view of FIG. 1.

FIG. 5 is a right side view of FIG. 1.

FIG. 6 is a top plan view of FIG. 1; and,

FIG. 7 is a bottom plan view of FIG. 1.

The invention is a sealing boot for a compressor.

No claim is made to portions which are not shown. The dash-dash lines indicate disclaimed environmental subject matter to which no claim is made. The surfaces are lined for contour.
